UNITED STATES PATENT OFFICE.

JOHN J. KELLY, OF HOLYOKE, MASSACHUSETTS.

CALENDAR.

1,373,744.

Specification of Letters Patent.

Patented Apr. 5, 1921.

Application filed February 18, 1920. Serial No. 359,519.

To all whom it may concern:

Be it known that I, JOHN J. KELLY, a citizen of the United States, residing at Holyoke, in the county of Hampden and 5 State of Massachusetts, have invented certain new and useful Improvements in Calendars; and I do hereby declare the following to be a full, clear, and exact description of the invention, such as will enable others 10 skilled in the art to which it appertains to make and use the same.

The object of this invention is to provide a perpetual or continuing calendar adapted for adjustment from month to month and 15 year to year, and limited in range of usefulness, if at all, only by the year designator, in that the month, week and day designations may be varied to suit any conditions which may arise and with the minimum of 20 effort and loss of time on the part of the operator, and with this object in view the invention consists in the construction and combination of parts of which a preferred embodiment is shown in the accompanying 25 drawings, wherein—

Figure 1 is a front view of the calendar.

Fig. 2 is a rear view of the same.

Fig. 3 is a transverse section on the plane indicated by the line 3—3 of Fig. 2.

30 Fig. 4 is a detail view of the day indicating slide showing the front thereof.

Fig. 5 is a similar view of the day indicating slide showing the rear thereof with means for concealing superfluous day designations or dates.

The device consists principally of a base 10 which may be a suitable card or plate, provided with a group of openings 11 for the exposure simultaneously of the day 40 designations of any given month, the horizontal sets or series of these openings being respectively designated by the days of the week arranged as shown in a column 12 as at the left of the group of openings. Also 45 at one side of the space occupied by the said group of openings may be arranged an opening 13 for the inclosure of a month designation, the names of the months being carried by a slide 14 fitted adjustably in a guide 15

50 extending from the rear surface of the base or board, while at the opposite side of said group of day openings may be arranged spaces 16 for the exposure of numerals representing the year, each numeral being carried by a separate slide 17 mounted in a guide 18 as shown in Fig. 2, and each of said

slides has a series of numerals so that any desired combination may be provided to represent the year number.

Fitted in suitable guides 19 also on the rear side of the board or plate are the edges of a day indicating slide 20 having represented thereon a group of numerals carried in columns and spaced to correspond with the openings 11 in the board or plate, said 65 slide being adjustable to arrange the proper portion of a group of numerals for exposure through said openings 11 to correspond with a true calendar, or in other words to arrange the numeral 1 of said group opposite 70 the week designation corresponding with the month of the year for which the calendar is set. It will be noticed that by means of the adjustment of the slide all of the possible combinations in designating the days 75 of the selected month may be fulfilled, and in order that those numerals of the group represented on the slide which are superfluous in any month such as those representing the thirty-first day or the thirtieth, 80 twenty-ninth and thirty-first for February, or the thirtieth and thirty-first for February leap year may be concealed so as not to cause confusion in reading the calendar; the slide 20 is longitudinally slotted as shown at 21 85 to form intervening guide strips 22 upon which are mounted auxiliary concealing slides 23 either or both of which may be moved as required to cover the superfluous day indicating members so that they may 90 not be exposed through the openings 11 in the plate or board. Owing to this construction the arrangement of the openings 11 may be made to suit all conditions which may arise in connection with monthly calendars without necessitating separate month slides or a 95 variable arrangement of the week day designations.

It will also be noticed that the adjustment from month to month involves merely the 100 changing of the month slide and of the week day designating slide together with such supplemental adjustment of the auxiliary slides as may be necessary to conceal the superfluous numbers.

105 What is claimed is:—

1. A calendar comprising a base provided with a group of openings for the exposure of the day designations of any given month arranged in vertical and horizontal rows, 110 parallel rows of openings having day designations associated therewith, a day indicat-

ing slide mounted on the rear of the base and provided with a group of day indicating numerals arranged in vertical and horizontal rows to register with the group of openings in the base for exposure therethrough, said slide being movable on the base in line with the day designations, and concealing slides mounted on the day indicating slide to cover surplus numerals thereof.

10 2. A calendar having a base provided with slots, a slide movable across said slots and having day indications for exposure therethrough, a slide disposed laterally of said slide having year indications, another slide 15 disposed laterally of the first slide having

month indications, said base having slots for exposure of the year and month indications therethrough, retainers at the sides of the first slide, said first slide being provided with slots to define strips, concealing members slidably mounted on the strips, and retainers for the second and third slides fastened to the base and overlapping the first retainers. 20

In testimony whereof I affix my signature 25 in presence of two witnesses.

JOHN J. KELLY.
